STEAM HEATING SYSTEM

John B. Stickle, Indianapolis, Ind.

Application July 13, 1929, Serial No. 378,128

5 Claims.

(Cl. 237—9)

This invention relates to the so-called "single pipe" system of steam heating and a control therefor responsive to weather conditions.

The object of the invention is to provide a single pipe steam heating system wherein the heat supply is regulated according to weather conditions to give more heating comfort with the maximum efficiency of steam consumption and fuel consumption. Certain features apply equally to other heating systems than the single pipe system.

Heretofore a common method of control of steam heating has been by direct control of the steam pressure or "heating pressure" in the pipe lines supplying steam to the radiating surfaces. This steam pressure is usually maintained above atmospheric pressure. By reducing heating pressure considerably below atmospheric pressure when heating requirements are not severe, important savings in steam consumption may be made since the temperature of steam decreases rapidly with a decrease in absolute pressure and since the radiation from the heating surface is directly proportional to the temperature difference between the steam therein and the room to be heated. For example, if the heating system of a building is designed, as is usually the case, to heat the building to 70 degrees Fahrenheit indoor temperature with five pounds per square inch of steam pressure above atmospheric pressure, 228 degrees Fahrenheit steam temperature and zero degrees Fahrenheit outdoor temperature, the standard radiation computations show that the building will be heated to the same indoor temperature with a steam pressure of twelve inches of vacuum, steam temperature 187 degrees Fahrenheit and an outdoor temperature of 18 degrees Fahrenheit. Therefore, when the outdoor temperature rises from zero degrees to 18 degrees Fahrenheit, the steam pressure may be reduced from five pounds above atmospheric to twelve inches vacuum below atmospheric and the steam temperature correspondingly reduced from 228 degrees Fahrenheit to 187 degrees Fahrenheit. Under these conditions, a saving of 26% in steam consumption may be made with no decrease in heating comfort. When the outdoor temperature rises higher than 18 degrees Fahrenheit, increased economies may be made by reducing the heating pressure to still lower absolute values.

In the single pipe heating systems in common use, the steam is supplied to the heating elements and the condensate returned therefrom through a single pipe. A single steam trap is

used to remove the condensate from the pipe line supplying a plurality of heating elements.

The principal feature of this invention resides in the provision of a single pipe steam heating system wherein the pressure of the steam in the heating elements may be carried either above or below atmospheric pressure as desired irrespective of the pressure in the boiler or other steam supply source.

Another feature of the invention resides in the provision of control means for varying the steam pressure or vacuum in the heating elements automatically in response to changes in weather conditions.

Another feature of the invention resides in the control of the heating pressure in response to wind velocity.

Another feature of the invention resides in the control of the heating pressure for different parts of the building in response to the direction and velocity of the wind.

In the case of buildings exposed to high winds, a given indoor temperature will require greater heating pressure when a high wind is blowing than will be required on a still day. In the case of large buildings particularly, a higher heating pressure will be required on the windward side of the building than is required on the leeward side. By means of certain features of the invention hereinafter described, the heating pressure for the whole building may be automatically increased when the wind velocity is above a predetermined point. By means of other features, the heating pressure on the windward side alone of a building may be similarly automatically increased, depending upon the direction of the wind.

Another feature of the invention resides in the provision of a time element by means of which sudden gusts of wind will not cause variation in heating pressure.

The details of the invention and the full nature thereof will be understood from the accompanying drawings and the following specifications and claims:

Fig. 1 is a diagrammatic representation of the principal parts of the heating apparatus used in carrying out the invention. Fig. 2 is an alternative form of connection for the pressure regulating valve used. Fig. 3 is an electrical wiring diagram for a variation of apparatus which may be used. Fig. 4 is an apparatus responsive to wind conditions which may be used for controlling heating pressure in different parts of a building. Fig. 5 is a wiring diagram for use with the apparatus of Fig. 4. Fig. 6 is a diagrammatic rep-

resentation of the principal parts of the heating apparatus used when heating of the various parts of a building is to be differentially varied.

In the form of apparatus illustrated in Fig. 1, 5 a steam pipe 10 furnishes steam to a pressure regulating valve 11 and thence to a pipe line 12 supplying a plurality of heating elements 13. The pipe line 12 is also used to return condensate from the heating elements by gravity and is connected 10 by pipe 14 to a suitable steam trap 15. A pipe line 16 carries condensate from the steam trap 15 to a vacuum pump 17 driven by an electric motor 18. Each of the heating elements 13 is fitted with 15 a thermostatic air valve 19 of a common commercial type. A pipe line 20 connects each of said air valves with the pipe line 16.

The regulating valve 11 is of the diaphragm type wherein a stem 21 is operated to open and 20 close the valve in response to the movements of a diaphragm contained in the housing 22. The housing 22 is divided by the diaphragm into two chambers, the chamber above the diaphragm being connected to the pipe line 16 by a pipe line 23 and the chamber beneath the diaphragm being 25 connected to the pipe line 12 by a pipe line 24. A lever 25 is pivotally mounted at 26 upon a portion of the valve body and is pivotally connected to the stem 21. Counterweights 27 are 30 attached at the outer end of the lever 25. By this means the stem 21 is lifted to close the valve when the pressure in pipe line 12 exceeds the pressure in pipe line 16 by a sufficient amount to lift the counterweights 27. If the difference in pressure 35 between pipe lines 12 and 16 is not sufficient to lift the weights 27 the valve 11 will be opened allowing steam to pass into pipe line 12 thereby raising the pressure therein to a point high enough to close the valve.

By this means a constant pressure differential 40 is maintained between the pipe line 12 and the vacuum line 16. This pressure differential may be varied as desired by varying the weights 27. The maintenance of a given pressure or vacuum in the pipe line 16 by means of the pump 17 will 45 automatically maintain a fixed pressure or vacuum in the pipe line 12 independent of the steam supply pressure in pipe 10. By increasing the 50 vacuum in pipe line 16 a vacuum may be produced in pipe line 12 and since the pressure in the heating elements or "heating pressure" is equal to the pressure in pipe line 12, the temperature of the steam in said heating elements will be reduced to the temperature corresponding to the said 55 vacuum.

55 By means of the thermostatic air valves 19 and the pipe connection 20, air may be withdrawn from the heating elements even when the pressure therein is below atmospheric pressure. Since the condensate is withdrawn from the steam 60 trap 15 by means of the vacuum pump, and since the pipe line 12 is always maintained at a higher pressure or lower vacuum than the pipe lines 16 and 20, the condensate drains freely from the 65 heating elements and there is proper air elimination from the heating elements, even though a vacuum is maintained therein.

Ordinarily, a pressure difference of approximately one pound per square inch or two inches of mercury is sufficient between pipe lines 12 and 70 16 for good drainage and air elimination. The regulating valve 11 is, therefore, ordinarily set to maintain this pressure difference and the vacuum pump is operated to give the proper pressure in pipe line 16 to maintain the desired heating 75 pressure in pipe line 12.

For automatic control of the vacuum pump motor thermostatic elements 28 and 29 and a regulator 82 are provided. The regulator 82 consists of a housing 83 divided into upper and lower chambers by means of a diaphragm contained therein. The lower chamber is connected to the pipe line 16, and the upper chamber is open to the atmosphere. The diaphragm is connected to a stem 84 adapted to operate a lever 85 of an electric switch box 86. A lever 87 is pivoted to 10 a member 88 supported by the housing 83 and is pivotally connected to the stem 84. A counter-weight 89 is carried on one end of the lever 87.

The thermostatic elements 28 and 29 are herein shown respectively inside and outside the building wall 30. These elements are connected by means of wires 31 with the motor controller 32 and the two elements are connected in series. The outdoor element 29 may be adjusted to close its circuit when the outdoor temperature is above 18 degrees Fahrenheit or any other predetermined temperature. The inside thermostat may be adjusted to close its circuit when the indoor temperature is above a second predetermined temperature,—usually about 70 degrees Fahrenheit. 25 The switch box 86 is connected by wires 90 to the wires 31 and is, therefore, in parallel with the two thermostatic elements. The motor controller 32 is of a standard type adapted to run the motor at a predetermined speed so long as both the 30 thermostatic elements are in the closed circuit condition or when the circuit is closed in the switch box 86. When the circuit in the switch box 86 is opened and one or both of the thermostatic elements is in the open circuit condition, 35 the motor will be stopped.

As an example of the operation of the system so far described, let it be assumed that the radiation surfaces are designed to heat a building properly to 70 degrees inside with zero degrees 40 Fahrenheit outside temperature with a heating pressure of five pounds per square inch above atmospheric pressure, corresponding to a steam temperature of 228 degrees Fahrenheit. It has been found by calculation and by experience that 45 when outside temperature is 18 degrees Fahrenheit, a heating system so designed will heat the building with no loss of heating comfort with a heating pressure of twelve inches of vacuum, corresponding to a steam temperature of 187 degrees 50 Fahrenheit. In that case, the weights 89 will be adjusted so that the regulator 82 operates to close the circuit in switch box 86 when a pressure of four pounds above atmospheric is reached in pipe line 16. The starting of the motor causes 55 the withdrawal of condensate and air from the pipes 16 and 20 until the pressure reduces below the said four pounds. The reduction of pressure results in the movement of the regulator 82 to open a circuit in switch box 86 thereby stopping 60 the motor. This intermittent operation of the motor results in the maintenance of a substantially constant pressure of four pounds above atmospheric in the pipe 16. If the weights 27 are 65 adjusted for a one pound pressure difference, a heating pressure of five pounds above atmospheric pressure is, therefore, maintained in the heating elements.

When the outdoor temperature and the indoor temperature are both increased above the temperatures for which the thermostatic elements are set, the circuits therein are closed and the motor and pump will be continuously operated. In the case assumed above, the speed of the motor will be adjusted to maintain a vacuum of 75

fourteen inches of mercury in the pipe lines 16 and 20 when operated continuously. This automatically reduces the heating pressure to twelve inches of vacuum.

5 A variation of the control is illustrated in Fig. 2 wherein the pipe line 24 connects pipe line 12 with the lower chamber of the housing 22 as before but the upper chamber of the housing is left open to the atmosphere by an opening 123. A lever 125 pivoted to the stem 21 and to the valve body at 126 extends in both directions and is adapted to receive weights 127 at either end. By placing the weights as illustrated in Fig. 2 a constant pressure below atmospheric pressure is maintained in pipe 12 independently of the steam supply pressure. By placing the weights 127 on the opposite end of the lever 125 a fixed pressure above atmospheric pressure may be maintained. In this case, the motor will be run at a constant speed to give as high vacuum as necessary for proper drainage with the highest expected vacuum in pipe line 12. The variations in the heating pressure or vacuum are then obtained entirely by manipulation of the counterweights 127.

25 With the apparatus just described, only one change of pressure is possible. Further increase of efficiency is obtained when pressure is changed by several steps. This is possible when the motor 18 is controlled by a plurality of thermostats as illustrated in Fig. 3. In this figure, thermostats 34, 35, and 36 may be adjusted to close their electrical circuits at successively increasing temperatures, for example at 10 degrees, 30 degrees and 50 degrees respectively. The electric circuits from these thermostats control a plurality of normally open relays 37 which are arranged to short circuit resistors 38 in the circuit of the shunt field 39 of the motor 18. By this arrangement the speed of the motor and consequently the speed of the vacuum pump is varied through successive steps, depending upon the temperature at the thermostats.

45 It is also possible to vary the speed of the pump by means of any common variable speed drive interposed between the pump and its driving motor and to control the ratio of said variable speed drive by the thermostats.

50 When it is desired to vary the heating pressure in different parts of the building in accordance with weather conditions, an arrangement of parts is used, such as shown diagrammatically in Figures 4, 5 and 6. In Fig. 6, heating elements 213 are divided into four groups indicated respectively by the letters N, E, W and S. These groups 55 may be considered as supplying the heating requirements for the north, east, west and south sides of the building respectively. Each group of heating elements is supplied with steam by a steam pipe 212 which also acts as condensate return pipe in the manner described. Each of the pipes 212 is connected to a steam main 210 by means of a regulating valve 211 and suitable branch pipes 210a. Each of the heating elements is fitted with a thermostatic air vent 219 and the air vents of each group of radiators are connected to an air removal pipe 220. The pipes 220 are all connected to a common air and condensate line 218 which is in turn connected to a pump 217 driven by a motor 218. A steam trap 215 is connected by means of a pipe 214 to each of the pipes 212 and serves to remove the condensate from the said pipes. Each of the traps 215 is connected to the pipe 216.

75 Each of the regulating valves 211 is of the diaphragm type wherein a stem 221 is operated to

open and close the valve in response to the movement of a diaphragm contained in a housing 222. The housing 222 is divided by the diaphragm into two chambers, the chamber above the diaphragm for each valve being connected to the pipe line 216 by pipe lines 223 and the chamber beneath the diaphragm for each valve being connected to the corresponding pipe line 212 by a pipe line 224. A lever 225 is pivotally mounted at 226 upon a portion of each of the valve bodies and is pivotally connected to the corresponding stem 221. Counterweights 227 are attached to each of the levers 225. By this means, each of the stems 221 is lifted to close its valve when the pressure in the corresponding pipe line 212 exceeds the pressure 15 in pipe line 216 by a sufficient amount to lift the counterweights 227.

20 Each of the valves 211 has associated therewith a solenoid carried on a portion 241 of the housing 222 and numbered respectively 75, 76, 77 and 78 for the east, west, south and north groups of heating elements respectively. A plunger 242 for each solenoid is supported on a spring 243 suspended from the end of the corresponding lever 225. When the solenoids are deenergized, the 25 springs and plungers hang as dead weights on the levers 225 and serve as additional weights to the counterweights 227. By energizing the solenoids, the plungers are pulled down against the action of the springs and a force is exerted on the 30 levers 225, depending upon the strength of the springs. By this means, each valve 211 functions to maintain a predetermined difference in pressure between the condensate and air removal pipe 216 and the corresponding steam pipe 212. When 35 the solenoid is not energized, this pressure difference depends only upon the weight of the solenoid plunger, the spring and the counterweight 227. When one of the solenoids is energized, however, 40 a greater pressure difference will be maintained in the corresponding pipe line 212. Thus the energizing of one of the solenoids 75, 76, 77 or 78 serves to increase the heating pressure in the portion of the building controlled thereby.

45 The pressure in the pipe line 216 is controlled by controlling the operation of the motor 218. This may be done in the manner previously described for the apparatus shown in Figure 1 or by the use of a variable speed motor control as shown in Figure 3.

50 Fig. 4 illustrates a form of electric apparatus responsive to the direction and velocity of wind and used to control the heating pressure for different parts of the building. A vertical shaft 44 is carried on a suitable step bearing 45 and a bearing 46 in the housing 47 and cover 48 respectively of a switch box. Said box may be located at a convenient position, preferably on the roof 49 of the building. A weather vane 50 is carried on the upper end of the shaft 44 and rotates the said shaft in response to changes in wind direction. Carried on the said shaft within the switch box is an arm 51 of insulation material carrying spring contact members 52 adapted to engage contact members 53, 54, 55, 56 and 57. 55 The last-mentioned contact members are carried on an insulation piece 58 supported within the housing 47. The contact member 53 is circular in form and is always in contact with its corresponding member 52. Contacts 54, 55, 56 and 57 are arcuate in form as shown in Fig. 5 and are adapted to contact with their respective members 52 when the wind is from the east, west, north or south respectively.

60 A shaft 59 is carried on suitable bearings 60 and 75

61 in the housing 62 and the cover 63 respectively of a second switch box also mounted in a convenient position on the roof of the building. Carried on the upper end of the shaft 59 is a wind gauge wheel 64 of the general type used by the United States Weather Bureau in measuring the velocity of the wind and adapted to rotate at a velocity proportional to said wind velocity. Carried on the shaft 59 within the housing is a usual 10 type of fly-ball governor indicated generally by the numeral 65. Pivotedly mounted within the housing is a bell crank 66 carrying on one arm a contact member suitably insulated therefrom and adapted to contact with a second contact member 15 68 carried upon and suitably insulated from the housing 62. The opposite arm of the bell crank 66 is associated with the movable member 69 of the fly-ball governor 65 to close the contact between contact members 67 and 68 when the fly-ball 20 governor has reached a predetermined speed. By adjustment of the actuating spring 70 of the fly-ball governor, this contact may be made to occur at any desired wind velocity.

The electrical wiring for this control apparatus 25 is shown in Fig. 5 wherein a pair of lines 71 lead from a suitable source of electric potential to the double pole knife switch 72. One pole of said switch is connected by line 73 to the contact member 68. The contact member 67 is connected by line 74 to the contact member 53. Contact members 52 are electrically connected to each other. Contact members 54, 55, 56 and 57 are connected respectively to solenoids 75, 76, 77 and 78. A common return line 78a leads from the 30 opposite terminal of each of these solenoids to the contact member 79 of a time relay switch. The opposite contactor 80 of the time relay switch is connected to the second pole of the knife switch 72. A solenoid 81 actuates the time relay switch 40 and is connected by one terminal to the contact member 67 and by the opposite terminal to the contact member 80 of the time relay switch. This switch is of a common form wherein contact is made between contact members 79 and 80 only 45 after solenoid 81 has been continuously actuated for a predetermined length of time.

By the operation of this circuit, the contact 50 67-68 is made only when the wind velocity has reached a point which will cause a difference in the heating required in different parts of the building. The closing of the said contact actuates solenoid 81 and, at a predetermined time thereafter, the 79-80 contact is closed. The latter contact, therefore, is not closed until the 55 predetermined wind velocity has been maintained for a predetermined length of time. Thus a sudden gust of wind will not actuate the apparatus.

The closing of contacts 67-68 makes a circuit 60 through line 74, contact 53, the contact members 52 to one of the arcuate contacts, depending upon the direction of wind velocity. Each of the arcuate contacts is connected to a corresponding pressure control solenoid and the circuit is completed through the common return line 78a to the knife switch 72 when the 79-80 contact is made as before described. By this method, a north wind, for example, blowing at a predetermined velocity for a predetermined length of time, will 65 actuate solenoid 77 to raise the heating pressure on the north side of the building. Similarly, a west wind will raise the heating pressure on the west side of the building. By the overlapping of the arcuate contacts as shown in Fig. 5, 70 a northwest wind will actuate both solenoids 76

and 77 to raise the heating pressure on both the north and west sides of the building.

In the case of small buildings or wherever it is desired to increase the heating pressure in the whole building when a high wind is blowing, regardless of the wind direction, the wind direction controller may be omitted and all of the solenoids may be operated directly from the wind velocity controller. In this case only one regulating valve 11 would be required for the entire building but 10 as many could be used as convenient. The wind control apparatus herein shown may also be used independently of the particular form of apparatus herein described. For example, a common form of pressure-reducing valve or valves may 15 be used and controlled independently of the return line vacuum to increase the heating pressure as desired for variation in wind velocity and direction.

It is to be appreciated that several variant 20 forms of the standard apparatus such as steam traps 15, thermostatic valves 19, heating elements 13, etc. may be used without departing from the invention. As an example, a common form of U-bend water seal may be used in place of the 25 steam trap. In the following claims the term "steam trap" is intended to include such equivalent structures. In the claims the word "pressure" indicates pressures both above and below atmospheric pressure.

The invention claimed is:

1. A steam heating system including a steam supply main, a radiator, a secondary pipe line for supplying steam from said main to said radiator, a regulating valve interposed between said secondary pipe line and said steam supply main, a steam trap receiving condensate from said radiator, a vacuum pump, a condensate removal pipe line connecting said steam trap and said vacuum pump, connections between said secondary pipe line, said condensate removal pipe line and said regulating valve for operating said regulating valve to maintain a substantially constant pressure difference between said pipe lines, a regulator associated with the condensate removal pipe line and controlling the operation of said pump to maintain a substantially constant condensate removal pressure when heating requirements are relatively severe, and other means operating in response to decrease in heating 50 requirements for controlling said pump to maintain a lower condensate removal pressure.

2. A steam heating system including a steam supply main, a radiator, a secondary steam pipe supplying steam from said main to said radiator, a regulating valve interposed between said steam supply main and said secondary steam pipe, an air removal valve for removal of air from said radiator, a pump, an air removal pipe connecting said air removal valve and said pump, connections between said secondary steam pipe, said air removal pipe and said regulating valve for operating said valve to maintain a substantially constant pressure difference between said pipes, a regulator associated with said air removal pipe to control the operation of said pump to maintain a substantially constant air removal pressure when heating requirements are relatively severe, and other means operating in response to a decrease in heating requirements for controlling said pump to maintain a lower air removal pressure and thereby to maintain a correspondingly lower pressure in said steam pipe.

3. A steam heating system including a steam supply pipe, a radiator, secondary pipe line sup-

- plying steam from said steam main to said radiator, a pump, an air removal pipe line connecting said pump and radiator for removal of air therefrom, thermostatic apparatus located in 5 a region whose temperature is indicative of the heating requirements of the system, means controlled by said thermostatic apparatus and operating said pump to increase the speed thereof and reduce the pressure in said air removal line 10 in response to an increase in temperature at said thermostatic apparatus and to decrease the speed of the pump and thereby increase the pressure in said air removal pipe in response to a decrease in temperature at said thermostatic apparatus, a 15 regulating valve interposed between said supply main and said secondary pipe line, and a differential controller connected to said secondary pipe line and to said air removal pipe line and operating said valve to throttle steam flow to said secondary pipe line in response to a decrease in pressure in said air removal pipe and to increase said steam flow in response to an increase in pressure in said air removal pipe, said controller being biased 20 to maintain a sufficient pressure difference between said secondary pipe line and said air removal pipe line sufficient for adequate condensate removal.
4. A steam heating system including a steam supply main, a radiator, a secondary pipe line supplying steam from said steam main to said radiator, a condensate pipe receiving condensate drained from said radiator, a condensate removal pump connected to said condensate pipe, thermostatic apparatus located in a region whose 25 temperature is indicative of the heating requirements of the system, means controlled by said thermostatic apparatus and operating said pump to increase the speed thereof and reduce the pressure in said condensate removal line in response to an increase in temperature at said thermostatic apparatus and to decrease the speed of the pump and thereby increase the pressure in 30 said condensate removal pipe in response to a decrease in temperature at said thermostatic apparatus, a regulating valve interposed between said supply main and said secondary pipe line, and a differential controller connected to said secondary pipe line and to said condensate removal pipe line and operating said valve to throttle steam flow from said supply main to said secondary pipe line in response to a decrease in pressure in said condensate removal pipe line and to increase said steam flow in response to an increase in pressure in said condensate removal pipe line, said controller being biased 35 to give a pressure difference between said secondary pipe line and said condensate removal pipe line sufficient for adequate condensate removal.
5. A single pipe steam heating apparatus including a steam supply main, a plurality of pressure regulating valves, pipe lines supplying steam from said supply main to said regulating valves, a plurality of groups of radiators, a plurality of branch pipe lines each supplying steam from one 40 of said regulating valves to one of said groups of radiators and each returning condensate from its associated radiators, a plurality of steam traps each receiving condensate from one of said branch pipe lines, an air removal pipe line removing air from said radiators, a pump operating to remove air from said air removal pipe line and condensate from said steam traps, a plurality of regulators each operating one of said regulating valves to maintain a substantially constant pressure difference between said air removal pipe line and its associated branch pipe line, and each of said regulators being adjustable to give a predetermined pressure difference to each group of heating elements independent of the others, a device responsive to wind direction and velocity for controlling said adjustment, and a timing element by means of which said adjustment control device is operable only when a predetermined wind velocity has been maintained for a predetermined length of time.

JOHN B. STICKLE.
